US0D1102429S

(12) **United States Design Patent** (10) **Patent No.:** **US D1,102,429 S**
(45) **Date of Patent:** **** Nov. 18, 2025**

(54) **SCANNER**

(71) Applicant: **Hand Held Products, Inc.**, Charlotte, NC (US)

(72) Inventors: **Yapeng Shi**, Charlotte, NC (US); **Huizhen Xu**, Charlotte, NC (US); **Libo Chen**, Charlotte, NC (US)

(73) Assignee: **HAND HELD PRODUCTS, INC.**, Charlotte, NC (US)

(**) Term: **15 Years**

(21) Appl. No.: **29/917,236**

(22) Filed: **Nov. 17, 2023**

(30) **Foreign Application Priority Data**

Jun. 1, 2023 (CN) 202330332583.8

(57) **CLAIM**

The ornamental design for a scanner as shown and described.

DESCRIPTION

FIG. 1 is a perspective view of a scanner showing our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken lines depict portions of the scanner that form no part of the claimed design.

1 Claim, 7 Drawing Sheets
